(57) **CLAIM**

The ornamental design for a paint can cap as shown and described.

DESCRIPTION

FIG. 1 is a front perspective view of a paint can cap showing my new design;

FIG. 2 is a rear perspective view of a paint can cap of FIG. 1;

FIG. 3 is a front plan view of the paint can cap of FIG. 1;

FIG. 4 is a side plan view of the paint can cap of FIG. 1;

FIG. 5 is an opposite side plan view of the paint can cap of FIG. 1;

FIG. 6 is a top plan view of the paint can cap of FIG. 1;

FIG. 7 is a bottom plan view thereof of the paint can cap of FIG. 1; and,

FIG. 8 is a front perspective view of the paint can cap of FIG. 1, illustrating the paint can cap on a can.

In FIG. 7, the broken lines show portions of a paint can top that form no part of the claim.

In FIG. 8, the broken lines depicts a can that forms no part thereof.

1 Claim, 7 Drawing Sheets
